UNITED STATES PATENT OFFICE.

OTTO BECKER, OF BERLIN, GERMANY.

MACHINE FOR GRINDING KNIVES, PRINCIPALLY THOSE OF SAUSAGE-MACHINES OR THE LIKE.

SPECIFICATION forming part of Letters Patent No. 700,293, dated May 20, 1902.

Application filed April 9, 1901. Serial No. 55,045. (No model.)

To all whom it may concern:

Be it known that I, OTTO BECKER, a subject of the Emperor of Germany, residing and having my post-office address at 46 Weidenweg, Berlin, Germany, have invented a new or Improved Machine for Grinding Knives, Principally those of Sausage-Machines or the Like, of which the following is a specification.

This invention relates to a new or improved machine for grinding knives, principally those of sausage-machines and the like.

The necessary hollow grinding or sharpening of blades or knives of sausage-machines was hitherto connected with great inconveniences and expense, since the knives could not be ground by the butchers themselves, but had to be sent to grinding establishments, where they were ground by hand on emery-wheels. Of course it could not be avoided in this process that the knives were often burned, owing to insufficient attention being paid to their cooling; but, above all, great skill of the grinder was required in order to produce the necessary perfect hollow grinding, according to the object of the knife, by means of moving the blades of the knife to and fro on the emery-wheel by hand. Since the knives are provided with several blades, generally with four, arranged crosswise, which in order to cut properly must have exactly the same hollow grinding, it was quite impossible to fulfil these conditions by means of the process described above, and the edges of all the blades were often straightened exactly in the same manner, in consequence of which a correct cut was never produced.

The object of the present invention is to remove all these inconveniences. By means of the new grinding apparatus all butchers, and even other persons without any special knowledge of grinding, are able to grind the knives without further difficulty in a mechanical way, and so that they fulfil all conditions by which the hollow grinding of all blades of the knives is perfectly uniform whether the knife is ground on one or both sides and independent of its construction. Burning the knives is also avoided by means of a cooling device. While formerly the knife had to be held by hand against the revolving emery grinding-wheel and moved to and fro, it is only necessary in the improved grinding apparatus to

place the knife in a holding device and then put the emery-wheel into revolution, by which the blades of the knife adjusted against the said wheel are all perfectly hollow ground in the same manner. In order to grind the following blade exactly in the same manner as the first one, the knife need not be removed and reinserted in its holder; but by means of a simple manipulation the said following blade is put into the position previously occupied by the first one, whereupon the grinding takes place. As all the blades of the knife are ground in exactly the same manner, they must necessarily all be perfectly uniform, and the following blades are given the same hollow grinding as the first one by means of constantly retaining the same position of the knife against the emery-wheel.

A form of construction of the present invention is shown in the annexed drawings, in which—

Figure 1 shows a side view of the grinding apparatus; Fig. 2, a plan view; Fig. 3, a front view. Fig. 4 shows the adjustment of the apparatus for the grinding of the second side of the blade of double-edged knives. Fig. 5 is an elevation of one form of knife on an enlarged scale, and Fig. 6 is a plan view thereof. Fig. 7 is an elevation of a second form of knife, and Fig. 8 a plan view thereof. Fig. 9 is an elevation of the knife-holder, and Fig. 10 a vertical cross-section thereof.

The grinding apparatus, which may be arranged so as to be driven either by hand or machinery, consists of a grindstone or emery grinding-wheel, which is put into revolution and simultaneously in a to-and-fro movement by the operating-wheel, and of a holder or support for holding the knife, the said holder or support being movable both in a longitudinal and transverse direction.

The emery grinding wheel or stone *a* is suitably fixed on a shaft *b*, adapted to revolve in brackets *d*, placed on a foundation-plate *c*. The displacement of this shaft in its axial direction corresponds to the greatest length of the corresponding blade of the knife and is effected by means of the following arrangement: At the end of the shaft *b* a lever *e* is arranged, which is eccentrically and revolvably fixed to a disk *f*, mounted on a shaft *h*, revolving in the block *g*. The operating-

wheel *k*, mounted on a shaft revolving in the bracket *i*, is connected with the pulley *l* by means of straps or cords, said pulley *l* being fixed to the shaft *b*, and simultaneously effects the revolution of the shaft *h*—for instance, by means of bevel-gears *m* and *n*—so that on the said wheel *k* being rotated the shaft *b*, with the emery-wheel *a*, is put into a rotation corresponding to the ratio of gear, the shaft *h*, with the disk *f*, being also revolved at the same time, by which the emery-wheel *a* revolves and at the same time is moved to and fro in an axial direction under the influence of the lever *e*, according to the throw of the eccentric. The blade of the knife held by the holder against the grinding-wheel is thus symmetrically ground along its whole length, and the hollow smoothness of the edge is perfectly uniform in every respect.

The knife-holder is constructed as follows: A disk *s*, revolvable on a shaft *r*, is arranged inclined to the emery-wheel *a*, the said disk *s* being arranged on a support *q*, which is placed on the base-plate *e* and which can be displaced longitudinally and transversely by means of screws *o* and *p*. In the said disk *s* a screw *t*, having right and left hand threads, is arranged in such a manner that on said screw being turned in the one or other direction two clamping-cheeks *u*, the ends of which are claw-shaped and project from the disk *s*, can be moved to or from each other, so that the knife *v*, which is adjusted on the disk *s* and into the socket of which the claws of the clamping-cheeks *u* catch on turning the screw *t*, is firmly fixed by means of the clamping-cheeks *u* being drawn apart. The disk *s* can be displaced in certain positions in such a manner that the blade of the knife *v* which at the moment is to be ground always occupies a horizontal position with reference to the grinding-wheel *a*. For this purpose holes *w*, corresponding to the number of blades—for instance, four—are provided in the disk *s*, into which holes a bolt *x* is inserted. In addition to the knives shown in Figs. 5 and 6 others with differently-arranged sockets are sometimes used, as shown in Figs. 7 and 8. In this case the disk *s*, for the purpose of enabling knives with their blades of the last-mentioned construction to be inserted into the determined position, is not only provided with four holes *w*, but with eight such holes for reception of the bolt *x*, so that also knives of this construction can be placed in position on the disk *s* of the same apparatus without any further manipulation.

In order that double-edged knives, as shown in Figs. 7 and 8, may be ground without trouble in the same apparatus, the support *q*, with the disk *s* thereon, can be displaced transversely to the emery grinding-wheel *a* by means of the screw *p*. Since the hollow grinding of the said double-edged knives on the left-hand side is contrary to that of the right-hand side, the knife, after all four blades have been ground on the right-hand side, is

removed and reinserted with the left-hand side placed in position on the disk *s* against the grinding-wheel. The grinding-wheel is then moved until it has reached the limit of its displacement in the outward direction, whereupon the disk *s*, with the knife, is brought by turning the screw *p* so far outward, as shown in Fig. 4, that the extreme edge of the grinding-wheel *a* forms a straight line with the socket of the knife, so that the blade which is placed inwardly is ground in the same manner as the outward blade in the before-mentioned single-edged knife. In order to grind all blades uniformly—that is to say, all the blades to the same extent—the displacement of the disk *s* toward the grinding-wheel *a* is limited by suitable means—for instance, an adjustable stop *z* or the like. A suitably-arranged water vessel serves to cool the knife, with its blades, during the grinding, in order to avoid a burning of the steel.

The operation of the apparatus is as follows: The knife *v* is so arranged on the disk *s* that the claws of the clamping-cheeks *u* catch into the socket thereof, and it is then fixed by means of turning the screw *t*. On revolution of the disk *s* on its axle *r* a blade of the knife is brought into the horizontal position and the said disk *s* held in this position by the bolt *x*. The disk on being revolved can also be automatically fixed in the determined position by means of an elastic bolt. The knife—that is to say, one of its blades—is then brought by the screw *o* against the emery-wheel and the latter put into rotation by means of the wheel *k*, by which the said emery grinding-wheel simultaneously receives a to-and-fro motion through the before-mentioned eccentric lever *e*, in consequence of which the blade of the knife is uniformly ground along its whole length. When one blade is sufficiently ground, the support *q* is stopped by the stop *z* or the like. The said support, with the knife thereon, is then moved back somewhat by turning the screw *o* in the opposite direction. The disk *s* is set free and turned so that the following blade of the knife is brought into the horizontal position previously occupied by the first blade. After the bolting or fixing of the disk *s* it is again brought against the grinding-wheel by turning the screw *o*, and on the said grinding-wheel being put into rotation the adjusted blade is ground in the same manner as the previous one. It can only be ground to the same extent as the first one, since the displacement of the disk *s* and the knife against the grinding-wheel is limited by the abutment *z* or the like. When the second blade is ground, it is removed from the grinding-wheel in the same manner as the first one, and the following blade is placed in position, and so on. The blade of the knife which at the moment is inserted is cooled during the grinding in a suitable water vessel to prevent it from being burned. If the knife is a double-edged one, as mentioned

- above, after grinding all blades on one side the knife is removed and reinserted with the other side against the grinding-wheel. Since the hollow grinding of this side is contrary to that of the side already ground, the inwardly-arranged blade is first ground instead of the outward one. For this purpose the grinding-wheel is moved outwardly to the extreme point of its displacement, and the disk *s*, with the knife thereon, is brought back by means of the screw *p*, as shown in Fig. 4, until the extreme edge of the grinding-wheel forms a straight line with the socket of the knife, so that on the grinding-wheel being rotated the same revolves and moves back, thus grinding the inwardly-arranged blade from the socket to the point in the same manner. When this has been done sufficiently, the abutment *z* is again fixed, the disk *s* turned until the following blade occupies the position of the first one, then stopped, and the blade which at the moment is adjusted for grinding is ground in the same manner as the previous one, and so on for all the blades of the knife.
- 25 It is evident that all blades are thus ground in a perfectly uniform manner. Since the disk *s* always occupies the same position with reference to the grinding-wheel—that is to say, all the blades always occupy the same horizontal position with reference to the section of the grinding-wheel whether the knife is ground on the one or other side—and since also the displacement of the knife and of its separate blades can be limited, a perfectly uniform grinding of all blades is obtained by means of this apparatus, which was hitherto impossible in grinding by hand. Also by means of this apparatus all inconveniences hitherto connected with the grinding of knives in sausage-machines and the like are thus completely removed, and the said apparatus is consequently rendered indispensable to all butchers, hotel-keepers, and the like.
- 45 What I claim is—
1. In a machine for grinding knives of the class described, the combination with a grinding-wheel, means for displacing said wheel in an axial direction and means for revolving said wheel, of a knife-holder consisting of a disk revolubly mounted on a support, screws for moving said support in a longitudinal and transverse direction, a stop for limiting the movement of said support, a bolt adapted to engage holes in said disk for holding the latter against revolution in the desired position, a right and left handed screw in said disk, clamping-cheeks on said screw, the jaws of which project beyond the surface of the disk and engage and adjustably hold the knife to be ground substantially as described.
  2. In a machine for grinding knives of the class described, the combination with a grinding-wheel, means for displacing said wheel in an axial direction and means for revolving said wheel, of a knife-holder consisting of a disk revolubly mounted on a support, screws for moving said support in a longitudinal and transverse direction, a stop for limiting the movement of said support, a bolt adapted to engage holes in said disk for holding the latter against revolution in the desired position, a right and left handed screw in said disk, clamping-cheeks on said screw, the jaws of which project beyond the surface of the disk and engage and adjustably hold the knife to be ground substantially as described.
  3. In a machine for grinding knives of the class described, the combination with a grinding-wheel, a shaft carrying said wheel, means for displacing said wheel and shaft in an axial direction, consisting of a lever pivoted eccentrically to a disk, and a shaft carrying said disk, said shaft being geared to a shaft carrying an operating-wheel, and means for rotating the grinding-wheel shaft, consisting of a pulley thereon, connected to said operating-wheel, of a knife-holder consisting of a disk revolubly mounted on a support, and at an angle to the grinding-wheel, screws for moving said support in a longitudinal and transverse direction, a stop for limiting the movement of said support, a bolt adapted to engage holes in said disk for holding the latter against revolution in the desired position, a right and left handed screw in said disk, clamping-cheeks on said screw, the jaws of which project beyond the surface of the disk and engage and adjustably hold the knife to be ground, substantially as described.

In witness whereof I have signed this specification in the presence of two witnesses.

OTTO BECKER.
